(57) CLAIM

The ornamental design for a stretch stick, as shown and described.

DESCRIPTION

FIG. 1 is a perspective view of a first embodiment of a stretch stick showing my new design;

FIG. 2 is a front view of the first embodiment of the stretch stick, the rear, top and bottom views are mirror images;

FIG. 3 is a left side view of the first embodiment of the stretch stick, the right side view is a mirror image;

FIG. 4 is a perspective view of a second embodiment of a stretch stick;

FIG. 5 is a front view of the second embodiment of the stretch stick, the rear, top and bottom views are mirror images;

FIG. 6 is a left side view of the second embodiment of the stretch stick, the right side view is a mirror image;

FIG. 7 is a perspective view of a third embodiment of a stretch stick;

FIG. 8 is a front view of the third embodiment of the stretch stick, the rear, top and bottom views are mirror images;

FIG. 9 is a left side view of the third embodiment of the stretch stick, the right side view is a mirror image;

FIG. 10 is a perspective view of a fourth embodiment of a stretch stick;

FIG. 11 is a front view of the fourth embodiment of the stretch stick, the rear, top and bottom views are mirror images;

FIG. 12 is a left side view of the fourth embodiment of the stretch stick, the right side view is a mirror image; and,

FIG. 13 is a front view of the stretch stick in a condition of use.

The broken lines in the drawings are for the purpose of illustrating environmental structure, which form no part of the claimed design.
